G. H. ENNIS

FASTENING DEVICE

Filed March 24. 1926

UNITED STATES PATENT OFFICE.

GEORGE H. ENNIS, OF NEW YORK, N. Y.

FASTENING DEVICE.

Application filed March 24, 1926. Serial No. 97,118.

This invention relates to an improvement in fastening of the general type forming the subject-matter of my prior Patent No. 1,557,996, granted Oct. 20, 1925, and the 5 present invention is especially adapted for use in connection with loose leaf binders although also adapted for use as a fastener for papers or the like.

The object of the present invention resides 10 in the provision of a device of this character wherein the parts of the fastener are positively interlocked and held against displacement accidentally or by virtue of the elasticity or depressing force which the leaves or 15 papers exert thereon.

In carrying out the present invention there is provided a base or suitable attaching element which may be secured to a part of the looseleaf book and which has a penetrating 20 prong connected thereto and adapted to be extended through the papers and to co-act with a tubular holding bar. The tubular holding bar and the penetrating prong have interengaging or interlocking parts which 25 positively secure the same together against accidental displacement although permitting the parts of the fastener to be disconnected at will.

Other objects and advantages reside in 30 certain novel features of the construction, arrangement and combination of parts which will be hereinafter more fully described and particularly pointed out in the appended claims, reference being had to the accompanying drawings forming a part of this 35 specification, and in which:

Figure 1 is a fragmentary perspective view showing a looseleaf book or binder and illustrating the present invention in 40 dotted lines,

Figure 2 is a view showing the present invention in elevation and the loose leaf book in section,

Figure 3 is a view in horizontal section on 45 the line 3—3 of Figure 2,

Figure 4 is a group view in perspective showing the parts of the fastener employed in Figures 1, 2 and 3,

Figure 5 is a similar view showing another 50 form of fastener and penetrating prong,

Figure 6 is a view in transverse section showing the construction of the tubular holding bar illustrated in Figure 5,

Figure 7 is a group view in perspective 55 illustrating another form of penetrating prong and tubular holding bar,

Figure 8 is a similar view illustrating still another form of penetrating prong and tubular holding bar,

Figure 9 is a group view in perspective 60 showing a modified form of penetrating prong and tubular holding bar,

Figure 10 is a fragmentary view in perspective showing a slight variation of the 65 form of penetrating prong illustrated in Figure 9,

Figure 11 is a sectional view showing how 70 the penetrating prong of Figure 10 co-acts with the tubular holding bar provided therefor,

Figure 12 is a detail perspective view 75 showing another modification of the invention, and

Figure 13 is a perspective view showing still another modification. 75

Referring to the drawings and more especially to Figures 1 to 4, inclusive, the numeral 1 designates generally a looseleaf book with which the fastening device constituting the present invention may be associated in 80 any desirable manner. In one modification illustrated for the sake of illustration the looseleaf book has flaps 2 and 3 between which the leaves 4 are positioned.

The fastening device constituting the present invention includes a base or attaching portion 5 having integral therewith or suitably connected thereto a penetrating prong 6. The base or attaching portion 5 engages or is secured to the flap 2 and the penetrating prong extends through an opening provided therefor in the flap 2 and through openings in the leaves 4. Along its edges the prong 6 is provided with notches 7 which define shoulders 8. A tubular holding bar 9 is provided and takes the form of an elongated tube constructed of a single piece of metal and having a slot 10 in its underface and extending from one end thereof to approximately the center portion of the bar. 100 The ends of the tubular bar are open. A locking lug 11 is bent up from the underwall of the tubular holding bar and obstructs the opening of the tube. This lug 11 has an inclined slot 12 therein through which the penetrating prong 6 is passed when either the prong or the bar are so-inclined as to bring the slot 12 and the prong 6 into parallelism or alignment.

In using this form of the invention the 110 penetrating prong is passed through the leaves and through the flaps 2 and 3 and then

is extended through the slot 12 to the desired extent while the slot 12 and the penetrating prong 6 are in the same plane or in alignment or parallelism. In other words, the extending end portion of the prong 6 is bent substantially parallel with the leaves before the holding bar is engaged therewith. When the penetrating prong has been inserted to the desired extent in the bar, the bar 9 is twisted so as to cause the shoulders 8 to engage the portions of the lug 11 which define the margins of the slot 12 and this positively interlocks the penetrating prong and tubular holding bar. The resiliency of the leaves will permit the required twisting or turning of the holding bar to permit engagement of the holding bar with the bent over portion of the prong and then will exert pressure on the holding bar, tending to prevent the holding bar from accidentally disengaging the prong.

In the form of the invention shown in Figure 5 and partially in Figure 6 the penetrating prong is designated generally at 15 and is the same as the prong 6 except that the notches 7 and shoulders 8 are omitted. A tubular holding bar 16 is provided and is constructed in all respects like the bar 9 except that its lug, designated at 17, does not have a slot therein and does not completely obstruct the opening or tubular holding bar, the lug leaving a space 18 through which the prong 15 may be passed when frictionally engaged by the lug 17. The lug 17 is made slightly resilient so that it can flex to some extent to permit insertion and removal of the penetrating prong although having binding or holding engagement in the desired adjustment.

40 In the form of the invention shown in Figure 7 a penetrating prong, designated generally at 20, is provided, and is similar to the prongs 6 and 15 with the exception that its shank is provided with a series of openings 21 of any desirable shape. A tubular holding bar 22 is provided for co-action with the penetrating bar 20 and is in all respects like the bars 9 and 16 except that its lug, which is designated at 23, is tapered or pointed and is somewhat resilient. This lug 23 flexes or bends to such extent as is necessary to permit the penetrating prong to be inserted into its bar or removed therefrom and yet in the desired adjustment this lug 23 engages in one of the openings 21 to hold the penetrating prong in the bar 22.

In the form of the invention shown in Figure 8 the penetrating prong 6 is employed and is identical with that shown in Figure 4. In the form of the invention shown in Figure 8, however, a different form of tubular holding bar is provided and is designated at 25. The tubular holding bar 25 is identical with the tubular holding bar 9 except that it has no lug formed with its

underside but has a pair of lugs 26 struck inwardly from its side walls and engageable with the shoulders 8. The lugs 26 are sufficiently resilient to enable them to flex as may be necessary to permit assembly and 70 disassembly of the prong and bar by the operator and yet hold the prong and bar in its desired adjustment.

In the form of the invention shown in Figure 9 a penetrating prong is designated at 30 and consists of a piece of wire integrally formed with a suitable base 31 which may be a laterally bent end portion of the wire. The prong 30 is provided with one or more notches 31' which are selectively co-operable 75 with lugs 32 struck in from a tubular locking bar 33 of cylindrical form. The tubular locking bar 33 has a slot 34 in its under portion extending from one end thereof to approximately the center of the bar. 85

In Figures 10 and 11 there is illustrated a slight variation of the form of the invention illustrated in Fig. 9. As illustrated in Fig. 10 the penetrating prong 30 instead of having notches 31' has lugs 36 struck therefrom and co-operable with an inwardly struck lug 37 provided on a tubular locking bar 38 as shown in Fig. 11. In certain angular adjustments the lug 36 passes the lug 37 of the holding bar 38 but the holding 95 bar 38 may be adjusted angularly to cause positive interlocking of the lugs 36 and 37.

As shown in Fig. 12 a tubular locking bar 50 may be provided and may have a slot 51 extending centrally of one of its flat walls 100 and enlarged, as at 52, at its inner end and may also have a slot 53 in a portion of the tubular locking bar that connects the flat walls thereof. In this form of the invention a penetrating prong 54 has its end bent at 105 right angles, as indicated at 55, and when the prong and locking bar are assembled, the flat body of the prong is passed through the slot 51 edge foremost and at this time the bent portion 55 of the prong is accommodated in the slot 53. When the prong 54 reaches the enlarged portion 52 of the slot 51 it is rotated to bring the laterally bent end portion 55 into the interior of the locking bar. This also so rotates the flat body 110 of the prong that its broad face is presented to the slot 51 whereby it cannot be removed unless the locking bar is rotated to present the edge of the body of the prong to its slot 51. 115

In the form of the invention shown in Fig. 13 a locking bar 60 is provided and has a slot 61 enlarged at its inner end, as at 62. This form of locking bar is adapted to co-operate with a string 63 on which the papers or ledgers of the book are carried. At least one end of the string is knotted, as at 64, this knot being too large to pass through the slot 61 or its enlargement 62. The purpose of the enlargement 62 is to permit some por- 120 125

tions of the knot to engage with the edges thereof so as to tend to prevent accidental displacement of the string through the slot 61. The laterally extending portion of the 5 knot 64 thus may be termed a lug on the tie member 63 for engaging with the slotted holding bar.

I claim:

1. A fastening device comprising a penetrating prong and a co-operable tubular holding bar, said penetrating prong and said holding bar having positively engageable locking means including a lug on the holding bar.
- 15 2. A fastening device comprising a penetrating prong and a co-operable tubular holding bar, said penetrating prong and said

holding bar having positively engageable locking means including a lug on the holding bar, said penetrating prong having 20 means positively engageable with the lug.

3. A fastening device comprising a penetrating prong and a cooperating tubular holding bar, said prong and said holding bar having co-engageable locking means including 25 a lug on the holding bar.

4. A fastening device comprising a tie member adapted to extend through a series of leaves, a slotted holding bar engageable with an end portion of said tie member, one 30 of said co-engageable members having a lug thereon.

GEORGE H. ENNIS.
